(57) **CLAIM**

The ornamental design for a cuff for surf leash, as shown.

DESCRIPTION

FIG. 1 is a front perspective view of a cuff for surf leash in a flat configuration, showing the new design;

FIG. 2 is a front elevation view showing the outer side thereof;

FIG. 3 is a rear elevation view showing the inner side thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front and right side perspective view of a cuff for surf leash in a curled configuration, showing the new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a rear and right side perspective view thereof;

FIG. 16 is a front perspective view of a cuff for surf leash in a flat configuration, showing the new design;

FIG. 17 is a front elevation view showing the outer side thereof;

FIG. 18 is a rear elevation view showing the inner side thereof;

FIG. 19 is a right side elevation view thereof;

FIG. 20 is a left side elevation view thereof;

FIG. 21 is a top plan view thereof;

FIG. 22 is a bottom plan view thereof;

(Continued)

FIG. 23 is a front and right side perspective view of a cuff for surf leash in a curled configuration, showing the new design;

FIG. 24 is a front elevation view thereof;

FIG. 25 is a rear elevation view thereof;

FIG. 26 is a right side elevation view thereof;

FIG. 27 is a left side elevation view thereof;

FIG. 28 is a top plan view thereof;

FIG. 29 is a bottom plan view thereof; and,

FIG. 30 is a rear and right side perspective view thereof.

The broken lines and structures they depict form no part of the claimed design.
